FIG. 1

FIG. 2

INVENTOR
Max Rosedale

BY Frank V. Rile
ATTORNEY

UNITED STATES PATENT OFFICE

128,146

DESIGN FOR A DISPLAY STAND FOR COMBS

Max Rosedale, New York, N. Y., assignor to E. I.
du Pont de Nemours & Company, Wilmington,
Del., a corporation of Delaware

Application September 14, 1939, Serial No. 87,222

Term of patent 3½ years

To all whom it may concern:

Be it known that I, Max Rosedale, a citizen of the United States and a resident of New York city, in the county of Bronx and State of New York, have invented a new, original, and ornamental Design for a Display Stand for Combs, of which the following is a specification, reference being had to the accompanying drawing, forming part thereof.

In the accompanying drawing:

I claim:

The ornamental design for a display stand for combs, substantially as shown.

MAX ROSEDALE.
